CLAIM

The ornamental design for a monogram, as shown and described.

DESCRIPTION

FIG. 1 is a front perspective view of a monogram showing my new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a front perspective view of the monogram design shown in FIG. 1 in the environment of a handbag.

The broken lines shown on claimed surfaces depict portions of the article and form no part of the claim. The broken lines showing a handbag in FIG. 7 depict environment and forms no part of the claim.

The JC JIMMY CHOO Monogram Design is a registered mark of J. Choo Limited.

1 Claim, 5 Drawing Sheets(56)
